his Attorney.

UNITED STATES PATENT OFFICE.

JAMES M. MERRITT, OF LOS ANGELES, CALIFORNIA, ASSIGNOR OF FORTY-ONE PER CENT. TO C. F. JAQUES, OF SAN FRANCISCO, CALIFORNIA.

AUTOMATIC STOVE OR THE LIKE.

1,394,424.

Specification of Letters Patent.

Patented Oct. 18, 1921.

Application filed December 13, 1920. Serial No. 430,208.

To all whom it may concern:

Be it known that I, JAMES M. MERRITT, a citizen of the United States, residing in Los Angeles, county of Los Angeles, State of California, have invented new and useful improvements in Automatic Stoves or the like, of which the following is a specification.

This invention has to do with improvements in automatic stoves, or the like, and 10 has for an object the provision of a simple, effective, reliable and easily accessible and adjustable mechanism of this character.

The invention relates particularly to automatic, or time controlled, cook stoves such 15 as gas stoves or ranges, although it is not specifically limited to any particular design or type of stove or necessarily limited to a gas stove or range. In the present disclosure I am setting forth the invention as embodied 20 in a typical gas range it being understood, of course, that such disclosure is for purpose of illustration and to facilitate a clear and accurate understanding of the invention.

In practice it has been found that automatic 25 stoves as heretofore proposed have possessed certain features and characteristics which make them more or less impractical and undesirable for use. It has been found that these devices are very difficult to adjust, that 30 they are not accurate and reliable, that they are rather complicated and expensive of construction, that they are not conveniently accessible for purpose of repairs and adjustments, etc.

It is a general object of the present invention to overcome undesirable features such 35 as those just outlined and to provide a neat, practical and commercially valuable automatic stove. By overcoming these undesirable 40 features without sacrifice of operation or utility the present invention provides a device superior to those heretofore provided and is therefore of particular practical and commercial value.

A distinctive feature of the invention is 45 the construction and arrangement which makes the various parts of the control device easily and quickly accessible for purpose of adjustment and repairs. In practice it sometimes occurs that repairs or adjustment are 50 necessary and that it is very important to make such repairs and adjustments quickly. With the construction provided by this invention all ordinary repairs and adjustments 55 can be quickly and easily made by the person

operating the stove and do not require the attention of a skilled mechanic or expert.

The various objects and features of the invention will be best and more fully understood from the following detailed description 60 of a preferred embodiment of the invention throughout which reference is had to the accompanying drawings in which—

Figure 1 is a face view, or front elevation, 65 of a typical gas cook stove, or range, embodying the present invention; Fig. 2 is a vertical sectional view of the apparatus provided by the invention being a view taken as indicated by line 2—2 on Fig. 4; Fig. 3 is a face view of the indicating dial; Fig. 4 70 is an enlarged detailed sectional view taken as indicated by line 4—4 on Fig. 1; Fig. 5 is an enlarged view of certain parts shown in Fig. 2; Fig. 6 is a detailed sectional view taken as indicated by line 6—6 on Fig. 5; Fig. 7 is a sectional view taken as indicated by line 7—7 on Fig. 6; Fig. 8 is a perspective 75 view of a part of the control mechanism; and Fig. 9 is an enlarged view of the main lever of the control mechanism. 80

Throughout the drawings numeral 10 designates a typical gas cook range comprising, generally, an oven 11, a broiler 12 arranged below the oven 11, a plurality of open burner devices 13 arranged to one side of the broiler 14 and oven, and the automatic control mechanism 14 provided by the present invention, all of which parts are arranged on and connected by a frame to form a unitary structure supported on suitable legs 15. The automatic control mechanism 14, provided by the present invention, may be arranged to control any one or several of the parts of the stove, for instance, as shown in the present disclosure it may be arranged to control the oven 11, or to control the stop valve 16 arranged in the pipe 17 which supplies the burner 17^a of the oven 11. It will be understood, of course, that such specific arrangement is for purpose of illustration and is not 95 intended to limit the scope of the invention in any way.

The automatic control mechanism 14 provided by the present invention is arranged and mounted so that its principal working parts, etc., are supported on a frame member 18 of the stove structure behind a panel 23. The main working parts of the mechanism are mounted on a single base 24 secured to the frame member 18 by suitable bolts 25. 100 110

A frame plate 20 extends upwardly from base 24 back of the panel 23 and carries a clock mechanism 21. The shaft or spindle 26 of the clock mechanism extends through an opening 27 in the frame plate 20, through a round opening 28 in the panel 23, and through an opening 29 in a dial plate 30^a arranged at the outer side of the panel 23. The panel 23 is preferably enameled and the dial 30^a is preferably held in place by screws 95 extending through spacers 96 and screw-threaded into the frame plate 20. The main lever 30 of the mechanism, which co-operates with the projection 45 on plate 43 to form a catch mechanism, is fulcrumed at 31 on an arm 32 and is arranged to extend between the clock mechanism 21 and the frame plate 20 below the spindle 26. The arm 32 is mounted on a shaft 35 which is carried by a bracket 36 extending from the base 24 and which extends through the panel 23 and carries a hand lever 70 on its outer end. An arm 52 is mounted on the inner end of the shaft 35 and is connected with the lever 53 of the valve 16 by a connecting rod 54. A roller 37 is carried on a pin 38 at the outer end of the arm 32 to engage a notch 39 in the lever 30. The outer end of the lever 30, as I will hereinafter term that end of the lever which extends between the plate 20 and clock mechanism 21, is guided by a guide bracket 40 mounted on the frame 20 while the opposite, or inner end, of the lever is connected with the base 24 by a tension spring 41. From inspection of the drawing, and particularly of Fig. 2 of the drawings, it will be seen that the lever 30 is so shaped, arranged and supported that the spring 41 tends at all times to move the outer end of the lever upwardly and to move the lever longitudinally, as indicated by the arrows in Fig. 2 of the drawings.

Plate 43 which is formed with a slot 44 and a projection 45 is mounted on the outer face of the frame plate 20 by means of a pin 46^a and a screw 46 so that the projection 45 extends through the opening 27 in the frame 20 and into an opening 47 in the lever 30. The opening 47 in the lever 30 comprises a longitudinal slot portion 48 at the inner end 50 of which there is a notch portion 49. The projection 45 co-operates with the opening 47, in the lever 30, to hold the outer end portion of the lever against upward movement and thereby causes the notched portion of the lever to be held in pressure engagement with the roller 37 on arm 32. When the projection 45 is in the slot portion of the opening 47 the lever 30 is free to be moved longitudinally by the spring 41 in the direction indicated by the arrow in Fig. 2 and when it is in the notched portion of the opening the lever is positively held in the position shown in Fig. 2. When the lever is in the position shown in Fig. 2 of the drawings the mechanism is in operating position with the valve

16 open, while when it is in the released position as shown in dotted lines in Fig. 5 the mechanism is out of operation and the valve 16 is closed. The plate 43 by being slotted and connected to the frame plate 20 by a pin 46^a and the bolt 46 is capable of adjustment so that the lever 30 may be held in different positions by the projection 45. Further, the various parts are arranged and proportioned so that the bolt 46 is opposite the opening 28 in the panel 23, as shown in the drawings.

When the parts are arranged, as shown in Fig. 2 of the drawings, the projection 45 is seated in the notched portion 49 of the opening 47 and the valve 16 is open. An arm or cam 50 on the spindle 26 of the clock mechanism 21 is arranged to rotate into engagement with the upper edge of the lever 30 to depress the outer portion of the lever 30 until the slotted portion 48 of the opening 47 is opposite the projection 45 thereby allowing the tension-spring 41 to act upon or move the lever 30 longitudinally in the direction indicated by the arrow in Fig. 2. Such movement of the lever 30 causes rotation of the shaft 35 due to the roller 37 being engaged by the end of the notch 39. This rotation of the shaft 35 moves the lever arm 52 and thereby causes closing of the valve 16 in the oven supply pipe 17 through the operating lever 53 of the valve 16 and the connecting rod 54. It will be readily understood how the plate 43 can be adjusted, so that the projection 45 holds the lever 30 in a position where it will be actuated by the cam 50 to bring the slot 100 portion 48 opposite the projection 45 upon the spindle 26 reaching a predetermined position. Ordinarily the plate 43 can be satisfactorily adjusted by loosening the screw 46 and then moving the lever to a position 105 where the notched portion of the opening 47 is opposite the projection 45 thus allowing the projection 45 to drop into and completely seat in the notched portion. If the screw 46 is then properly tightened to hold the plate 110 the lever will be securely and properly held by the projection until it has been engaged and moved by the cam 50.

The dial 30^a, mounted on the outside of the panel 23, is provided with suitable markings or graduations, as shown in Fig. 3. A hand 60 is adjustably clamped on the spindle 26 by screw 61 and is set to point to the zero mark on the dial when the spindle 26 is in position where the lever 30 is released 120 to move longitudinally in the direction indicated by the arrow in Fig. 2. The markings on the dial 30^a are preferably in minutes. A knob 62 is mounted on the outer end of the spindle 26 so that the clock mechanism and hand can be set, or so that the spindle 26 can be turned from the position where the arm 30 is released, so that the mechanism will remain in the "on" position as shown in Fig. 1 a predetermined length 125 130

of time or until the spindle has rotated from the position in which it was set to the position where the cam 50 moves or releases the lever 30. The graduations on the dial are 5 such that the hand will coöperate with them to indicate the position of the spindle relative to the released position, or will indicate how many minutes it will take for the spindle to move from the set position to the position 10 where the mechanism is released. For instance, if it is desired that the mechanism should remain in the "on" position, shown in Fig. 2, for twenty minutes the knob 62 may be rotated to bring the hand 60 opposite the graduation 20 whereupon the clock mechanism will immediately begin to rotate the shaft and therefore the knob, the hand, and the cam in the direction indicated by the arrow in Fig. 3, and will continue to rotate 15 the spindle for 20 minutes before it reaches the position where the lever 30 is released. To turn the stove on, and set the automatic control or cut-off mechanism, the time mechanism is set in the manner just described 20 and the lever 30 is moved to the position shown in Fig. 2 by turning of the hand lever 70. It will be obvious how the lever 70 can be turned to throw the lever 30 longitudinally in the direction opposite to that indicated by the arrow in Fig. 2 until the notched portion 49 of the opening 47 is opposite and in coöperation with the projection 45.

With the connection between the arm 32 35 and the lever 30 effected by a roller and slot construction, as hereinabove described it is possible to turn off or regulate the stove or oven by suitable manipulation of the hand lever 70 at any time before the clock mechanism 40 has rotated the spindle 26 to a position where the lever 30 will be released. For instance, the handle 70 may be turned at any time causing the roller 37 to pass through the notch 39 and cause rotation of the shaft 45 35 and thereby manipulation or turning of the valve 16.

With the construction provided by the present invention the mechanism may be easily, quickly and accurately adjusted to 50 release at the proper time either by adjusting the position of the hand 60 on the spindle 26 or by adjusting the position of the plate 43, or by both. Adjustment of the hand 60 may be very easily and quickly 55 made by simply releasing the clamping screw 61 and turning the hand to the desired position and then tightening the clamp screw 61. To adjust the plate 43 it is merely necessary to remove the knob 62 60 and hand 60 from the spindle 26 whereupon the dial 30 can be removed by releasement of the screws 95. With the dial 30 removed the plate 43 can be easily and quickly adjusted by suitable manipulation of the bolt 65 46. All adjustments of the mechanism may

be readily made from the front of the range and can be made without the aid of special tools of any kind. In practice the mechanism can be very accurately, easily and quickly adjusted in the following manner: 70 First remove the knob, the hand and the dial whereupon the plate 43 can be loosened to be free to move, throw the hand lever 70 until the projection engages and seats in the notched portion of the opening 47, tighten 75 the screw 46, replace the removed parts leaving the hand loose on the spindle, rotate the spindle by the knob until the lever 30 is released, and then set the hand to zero thus completing the adjustment. The range can 80 then be operated reliably and accurately without further attention or adjustment. If for any reason it is found that the mechanism does not trip accurately, say for instance, if the mechanism trips slow or fast, 85 suitable adjustment may be made in the position of the hand. It will be obvious how the present invention permits of quick simple and accurate adjustment and how it provides an extremely simple and inexpensive 90 structure. From inspection of the drawings it will be noted that the invention provides a neat, sightly, and simple mechanism and it will be understood how the mechanism provided by the invention is reliable and 95 effective in operation. The extreme simplicity of construction and arrangement assures reliable and accurate operation. For instance, the connection between the arm 32 and lever 30 being made by a roller and slot 100 prevents binding or sticking of that connection and assures smooth operation.

It will be particularly noted that the invention arranges the clock mechanism, frame plate 20, bracket 35, lever 30, etc., on a single 105 base 24 so that these parts can be totally and completely moved from the range as a unit in the event that it becomes necessary to make important repairs on them. In practice, this unitary structure can be easily and 110 quickly removed by simply releasing the connecting rod 52 and the bolts 25 and by removing the handle 70, the knob 62 and the hand 60.

Having described a preferred form of my 115 invention, I claim:

1. In a cook stove having a panel part and embodying a burner and a control valve for the burner, automatic time control mechanism for the valve comprising an adjustable 120 catch mechanism arranged back of the panel, to be adjustable from the front of the panel, and a clock mechanism adapted to release the catch mechanism.

2. In a cook stove having a panel part 125 with an opening and embodying a burner and a control valve for the burner, automatic time control mechanism for the valve comprising an adjustable catch mechanism arranged back of the panel to be adjustable 130

through the opening, and a clock mechanism arranged back of the panel adapted to release the catch mechanism.

3. In a cook stove, having a panel part and embodying a burner and a control valve for the burner, automatic time control mechanism for the valve comprising a catch mechanism arranged back of the panel, a clock mechanism arranged back of the panel and mechanism arranged back of the panel and 5 adapted to release the catch mechanism, and 10 an adjustable indicating device at the front of the panel.
4. In a cook stove, having a panel part and embodying a burner and a control valve for 15 the burner, automatic time control mechanism for the valve, comprising a catch mechanism arranged back of the panel, a clock mechanism arranged back of the panel and adapted to release the catch mechanism, and 20 an indicating device for the clock mechanism adjustable from the front of the panel independently of the clock mechanism.

5. In a cook stove having a panel part and embodying a burner and a control valve for 25 the burner, automatic time control mechanism for the valve, comprising an adjustable catch mechanism arranged back of the panel to be adjustable from the front of the panel, a clock mechanism arranged back of the 30 panel and adapted to release the catch mechanism, and an adjustable indicating device for the clock mechanism mounted on the front of the panel.

6. In a cook stove having a panel part with 35 an opening and embodying a burner and a control valve for the burner, automatic time control mechanism for the valve comprising an adjustable catch mechanism arranged back of the panel to be adjustable through 40 the opening, a clock mechanism for releasing the catch mechanism arranged back of the panel, and an adjustable indicating device for the clock mechanism removably arranged at the front of the panel, said device 45 including a dial forming a closure for the opening.

7. In a cook stove having a panel part and

embodying a burner and a control valve for the burner, automatic control mechanism for the valve comprising an adjustable catch 50 mechanism arranged back of the panel, a clock mechanism adapted to release the catch mechanism, and an indicating device for the clock mechanism arranged at the front of the panel, the catch mechanism and 55 the indicating device being independently adjustable.

8. In a cook stove having a panel with an opening and embodying a burner and a control valve for the burner, automatic time 60 control mechanism for the valve comprising an adjustable catch mechanism arranged back of the panel to be adjustable through the opening, a clock mechanism arranged back of the panel for releasing the 65 catch mechanism, and an indicating device for the clock removably arranged at the front of the panel, said device including a dial forming a closure for the opening.

9. In a time control mechanism, an adjustable catch device comprising a lever having an opening, an adjustable member having a projection adapted to coöperate with the opening, and releasable means for setting said member in fixed position. 70

10. In a time control mechanism, a catch device comprising a lever having a notch, a support for the lever comprising a roller adapted to engage the notch, and means for holding the lever and support in coöoperative 80 engagement.

11. In a time control mechanism, a catch device comprising a lever having a notch, a support for the lever comprising a roller adapted to engage the notch, and means for 85 yieldingly holding the lever and support in coöoperative engagement.

In witness that I claim the foregoing I have hereunto subscribed my name this 6th day of December, 1920.

JAMES M. MERRITT.

Witness:

VIRGINIA BERNINGER.
